Inventor;

E. M. Stevens

UNITED STATES PATENT OFFICE.

E. M. STEVENS, OF BOSTON, MASSACHUSETTS, ASSIGNOR TO ALFRED B. ELY, OF SAME PLACE.

ROUNDING-MACHINE.

Specification forming part of Letters Patent No. 43,958, dated August 23, 1864.

To all whom it may concern:

Be it known that I, E. M. STEVENS, of Boston, in the county of Suffolk and State of Massachusetts, have invented a new and useful Improvement in Rounding-Machines; and I do hereby declare that the following is a full, clear, and exact description of the construction and operation of the same, reference being had to the accompanying drawings, forming a part of this specification, in which—

Figure 1 is a top view; Fig. 2, a side elevation; Fig. 3, an edge view of the sliding carriage, showing the appendages to its under side.

Like parts are indicated by the same letters in all the drawings.

The nature of my invention consists, first, in the use of a stationary pattern, in combination, or connection with a traveling cutter; second, in combining a yielding cutter with a traveling-carriage, for rounding, paring, or cutting out leather and analogous substances to a pattern which may be stationary; third, in so constructing and arranging the traveling cutter that its cutting-edge shall substantially correspond with the center of motion of its shank; fourth, in so forming and arranging the traveling cutter that while in operation its edge shall be turned and presented at all times, so as to cut the material in a line substantially parallel to, or in the same plane with, the edge of the pattern; fifth, in so arranging the traveling knife that it may be adjusted to cut the edge of the leather, &c., to any required bevel; sixth, in the combination of a spring with the traveling cutter for the purpose of keeping the latter up to the pattern; and seventh, in so constructing the pattern and clamp that one or both of them may be turned for the purpose of cutting from the strip (heel and toe alternately) when the pattern is of such a form as to make it desirable.

To enable others skilled in the art to make and use my invention, I will now describe its construction and operation.

A is a cast-iron table or stand provided with legs B. The top of the table A is flat, and furnished with tracks or ways, C, D, and E, Fig. 1, raised about one eighth of an inch above the general surface, and planed or

smoothed, so that the frame which carries the rounding-knife may slide easily over them.

a' is a groove through the top of the table, between the track E and the form or plate b', the edge of which is parallel with the track E, and the surface of which is flush with the same, the form b' resting on starts from a cross-bar below the table and held in place by means of the screws G G.

H is a start projecting from and above the plate b'.

I is a removable pattern or guide, of the exact contour of the shoe-sole or other article to be pared or rounded, and against the edge of which the cutting-knife is pressed.

O is a vertical shaft passing through the plate b' and start H, its upper end entering a hole in the center of the pattern I, while its lower end is provided with a pinion, Q.

R is a sliding bolt, provided with a rack, (as shown by dotted lines in Fig. 1,) which engages with the cogs of pinion Q. By sliding out or in this bolt R it is obvious that the shaft O and the pattern I, which rests upon it, can be turned when it is required to cut heel and toe alternately.

P is a spiral spring, by means of which the pattern I, when not pressed upon from above, is lifted up so as to be free to turn.

d' d' are pins fast in the starts F F, and projecting up into holes in the pattern I, whereby the latter is held in place.

J is the clamp, the contour of which corresponds with that of the pattern I. The latter, however, projects slightly beyond the clamp, as shown in the drawings, Figs. 1 and 2. The bottom of this clamp, as shown in Fig. 2, has around its edge a row of conical points, the design of which is to press into the material to be cut or rounded and prevent the same from slipping.

K is a shaft passing through the center of the bar S, which rests on the studs T T, the lower end of said shaft entering a hole in the center of the clamp J, whereby the latter is raised and turned. The upper end of the shaft K is slotted so as to receive the lever L, which turns on the fulcrum g.

M M are little studs provided with projecting heads or shoulders, by means of which

the lever L and its appendages are kept down, as represented in Fig. 2, one arm of the lever passing under the shoulder of one stud and a spur from the opposite arm passing under the shoulder of the other stud.

U is a chain-belt of the ordinary construction, which passes around the spur-pulleys V under the table and approximately parallel with the groove a' , as represented in Figs. 1 and 2. One of the spur-pulleys turns on an axle, X, fast to a cross-piece under the table, and the other is fast to the top of the shaft W, which also turns in suitable bearings in a cross-piece under the table.

Y is a bevel-pinion attached to the lower end of the shaft W.

Z is a smaller bevel-pinion, fast to the shaft a, and engaging with the pinion Y.

b is a crank, and c a handle, by turning which the chain-belt U and its appendages are made to move.

d is the traveling carriage, the shape of which is shown in Figs. 1 and 2, the under side being smooth and resting on the raised tracks C D E. The inner point of this carriage extends a little beyond the groove a' , and it is provided on its under side with two pins or friction-rollers x x, (see Fig. 3,) which traverse in the groove a' , thereby guiding said carriage and keeping it at right angles to said groove. Between said friction-rollers is a pin, u, projecting downward through the groove a' into a link, h', which is attached to the chain U by means of the pivot i', whereby the carriage will be drawn along around the pattern I by the chain.

e is a plate, (the shape of which is shown in Fig. 1), which slides on suitable ways on the top of the sides of the carriage d, m m being cleats to keep the plate e in place. The sliding plate e is pressed toward the pattern I by means of the spring n, (the shape and position of which are shown in Fig. 1,) said spring being held in place by the set-screw o. The free end of this spring bears against a nub on one end of the lever P, which is attached to the bottom of the plate by means of the pivot q. More or less tension may be given to the spring n by moving the lever P, which is held in place at its outer end by the pin r, the latter being inserted in any one of the holes (shown in Fig. 1) on the outer edge of the plate e.

t is a sliding pin, held in place by means of the hasp f', which enters an annular groove in the same, the object of said pin being to hold the free end of the spring n, when pushed in behind it, for more conveniently inserting or arranging the rounding-knife.

s is a lever, one end of which is pivoted to one of the cleats m, the free end of the same extending beyond the opposite cleat.

j' is a pin projecting above the upper side of the plate e, the design of said pin being to

operate as a fulcrum for the lever s, by means of which the slide e and its appendages may be moved back from the pattern I. Projecting from the under side of the lever s is a short pin, which may be depressed so as to enter one of the holes in the right-hand cleat m, (see Fig. 1,) by means of which the slide e may be held back from the pattern I.

f is a block fitted into a corresponding slot in the end of the slide e, and confined by the pin g, on which it can be turned, so as to give any required inclination to the rounding-knife j.

h is a set-screw the inner end of which rests against the block f and prevents it from turning.

j is the rounding-knife, the shank i of which is round, and turns freely in its bearing in the end of the block f. The edge of the knife is intended to be opposite the center of the round shank i, so that it may always touch the pattern I. The side of the shank i which bears on the edge of the pattern I, turning and guiding the knife j, is slightly concave, so as to always touch said pattern without rocking on it.

k is an arm attached to the bottom of the shank i of the cutter, and l is a rubber or other suitable spring, the action of which arm and spring is to draw the edge of the knife from the edge of the pattern I when not forced up by the action of the spring n.

From the above description it is obvious that a strip of leather or other analogous substance placed upon the pattern I, and confined by the clamp J, will be cut or rounded to the exact contour of said pattern, and at any required bevel.

My invention is designed more particularly for "rounding" boot and shoe soles, all sizes and styles of which may be rounded with the same machine by the employment of patterns I of the size and style required, the spring n in all cases pressing the rounding-knife close to the pattern.

When required to cut heel and toe alternately from a large strip for the purpose of saving stock, the pattern I and clamp J may be turned as described above.

Having thus described the construction and operation of my improvement, what I claim in rounding-machines, substantially as and for the purpose described, is—

1. The use of a stationary pattern in combination with a continuously-traveling cutter.
2. Combining a yielding or sliding cutter with a traveling carriage.
3. So constructing and arranging the traveling cutter that its cutting-edge shall substantially correspond with the center of motion of its shank.

4. So forming and arranging the traveling cutter that while in operation its edge shall be turned and presented at all times so as to

cut the material in a line substantially parallel to or in the same plane with the edge of the pattern.

5. So arranging the traveling knife that it may be set or adjusted to cut the edge of the leather, &c., to any required bevel.

6. The combination of a spring with the traveling cutter for the purpose of keeping the latter up to the pattern.

7. So constructing the pattern and clam

that one or both of them may be turned for the purpose of cutting heel and toe alternately.

8. The lever *P*, in combination with the spring *n* and slide *e*, for adjusting the pressure of the rounding-knife to patterns of different sizes.

E. M. STEVENS.
